UNITED STATES PATENT OFFICE.

HARRY GUY HILL, OF WHITE SALMON, WASHINGTON.

LADDER-ADJUSTING MEANS.

1,266,466.

Specification of Letters Patent. Patented May 14, 1918.

Application filed July 17, 1917. Serial No. 181,145.

To all whom it may concern:

Be it known that I, HARRY G. HILL, a citizen of the United States, residing at White Salmon, in the county of Klickitat and State of Washington, have invented certain new and useful Improvements in Ladder-Adjusting Means, of which the following is a specification.

This invention relates to adjusting means for ladders and more particularly to means whereby a supplemental extension strip or piece may be clamped to the leg of a ladder so as to be slidably adjustable thereon.

One of the main objects of the invention is to provide a clamping device of simple construction and operation which may be readily applied to a ladder of standard construction. A further object is to provide a clamping device and operating means therefor which may be quickly and easily moved into tight engagement with the ladder leg and the extension piece mounted thereon so as to securely lock these two members together. A still further object is to provide a clamp composed of a minimum of parts which may be readily produced at small cost. Further objects will appear from the detailed description.

In the drawings:

Figure 1 is a fragmentary side view of a ladder with the clamping means applied,

Fig. 2 is a section on line 2—2 of Fig. 1, and

Fig. 3 is a section on line 3—3 of Fig. 1.

The leg 1 of the ladder is of usual construction being of rectangular shape in cross section. An extension piece 2 which is shaped similar to the leg 1 is mounted on the outer face of the leg so as to be slidable thereon. A metal plate 3 is fixedly secured to the outer face of extension piece 2 a short distance from the upper end thereof. An outwardly extending stud 4 is fixedly secured to strip 3 adjacent one end thereof, and the other end of the strip is provided with a central recess the sides of which form the two lateral guide fingers 5. An outer rectangular clamping jaw 6 is mounted about the extension piece 2 and the leg 1.

The outer arm 7 of this jaw extends across the outer face of strip 2 and is provided, at its rearward end, with a longitudinally extending slot 8 which loosely receives stud 4, a limiting nut 9 being threaded on the stud in front of the arm. The front arm 10 of the jaw 6 extends across the

front edges of leg 1 and piece 2. Arm 10 is loosely mounted through an eye 11 formed at the front end of the inner jaw 12 which is straight, and which is toothed as at 15 so as to grip ladder rail 1 tightly. The eye 11 is disposed at an angle to jaw 12, as shown, and the outer bar of this eye is in close engagement with the front edge of arm 10 of jaw 6. By forcing the arm 7 of the jaw away from extension piece 2, the outward pressure on this arm, being exerted intermediate the ends thereof, the arm will be caused to rock about the stud 4, thus swinging arm 10 outward and forward which results in forcing jaw 12 into tight engagement with the inner face of leg 1, the eye 11 being in biting engagement with arm 10, as clearly shown in Fig. 2 of the drawings. When the outer jaw of the clamp is operated in this manner, the ladder leg and extension piece are firmly secured together, as in Fig. 2 of the drawings, the eye 11 being forced into biting engagement with member 10.

A wedge disk 16 is rotatably mounted on plate 3 on a headed pin 17 secured at the longitudinal center of the plate. This disk tapers diametrically in thickness, as shown, and is provided with an integral operating handle 18. By turning the disk so as to force the thickened portion thereof beneath arm 7 of outer clamp jaw 6, the forward portion of the jaw will be swung outwardly and forwardly in the manner described, the edge of nut 9 acting as a fulcrum point for this operation of the jaw. This results in swinging front arm 10 of jaw 6 forwardly and outwardly forcing the jaw 12 toward the leg 1 so as to tightly grip the same. During this operation, the front arm 10 of jaw 6 is in engagement with the front edge of piece 2 so as to prevent forward movement of the same.

As will be noted more particularly from Fig. 1 of the drawings, the wedge disk 16 is positioned intermediate the plate 3 and the outer arm of the outer jaw, and the handle 18 for operating this disk is so disposed that, when the outer jaw has been forced outwardly to its extreme position, the handle is disposed substantially in parallelism with the extension piece 2. This avoids all unnecessary projections, such as would interfere with the use of the device on a ladder for the purpose specified, while producing a clamp capable of exerting a comparatively great clamping effect due to

the fact that the outer arm of the outer jaw is fulcrumed at its outer end, the wedge disk being positioned inside of the fulcrum point and acting in the same manner as a wedge, exerting outward pressure on the under face of this outer arm. The clamp constructed in this particular manner is well adapted for the purpose set forth, avoids all unnecessary projections, and is capable of exerting a powerful gripping effect.

An angle bracket or guide 19 is secured to piece 2 and fits about the rearward edge of leg 1 a short distance below the clamp. This bracket acts to secure the leg 1 against rearward movement independently of the extension piece 2 thus insuring that the toothed inner surface of the clamping jaw 12 will engage tightly with the inner face of the ladder rail 1. A pin 20 is inserted through the inner end of the forward arm 10 of outer clamping jaw 6 and serves to prevent complete withdrawal of this arm from eye 11.

In describing the application of the clamp I have referred to the various surfaces of the leg 1 and the extension piece 2 as inner and outer, and forward and rearward, for the sake of clearness in description, but it will be obvious that the clamp may be applied to the ladder leg and extension piece in any preferred manner.

In using my device an extension piece 2 is mounted on each leg or rail of the ladder. These extension pieces may be quickly and

easily adjusted independently longitudinally of the ladder rails by the clamping means above described. This renders it possible to adjust the effective length of each rail of the ladder so as to overcome any unevenness in the ground or surface upon which the ladder rests thus insuring a true and accurate set of the ladder. It will be obvious that the extension piece 2 can be of any desired length and can be secured on the ladder rail at any desired point intermediate the ends thereof.

What I claim is:—

In ladder adjusting means, a clamping device comprising an inner clamping jaw 50 provided at one end with an integral eye, a plate adapted to be secured to an extension piece 55 slideable on a ladder rail so as to vary the effective length thereof, an outer rectangular or L-shaped clamping jaw having its outer arm extending in parallelism with said inner jaw and loosely secured at its outer end to said plate adjacent one end thereof, the inner arm of said outer jaw being inserted through said eye, and a wedge member 60 rotatably mounted between said plate and the outer arm of the outer jaw for rocking said jaw upwardly away from the plate.

In testimony whereof I affix my signature 65 in presence of two witnesses.

HARRY GUY HILL.
